UNITED STATES PATENT OFFICE

149,700

DESIGN FOR A MASSAGE INSTRUMENT

Matthew M. Sky, Chicago, Ill.

Application December 26, 1946, Serial No. 135,778

Term of patent 3½ years

(Cl. D83—1)

To all whom it may concern:

Be it known that I, Matthew M. Sky, a citizen of the United States of America and a resident of Chicago, in the county of Cook and State of Illinois, have invented a new, original, and ornamental Design for a Massage Instrument, of which the following is a specification, reference being had to the accompanying drawing, forming a part thereof, and in which:

Fig. 1 is a perspective view of a massage instrument showing my new design;

Fig. 2 is an end view of the same;

Fig. 3 is an end view of the same, opposite to that shown in Fig. 2.

I claim:

The ornamental design for a massage instrument, as shown.

MATTHEW M. SKY.
